GUIDER

Filed Jan. 13, 1931

UNITED STATES PATENT OFFICE

FRANK A. LANE, OF PROVIDENCE, RHODE ISLAND, ASSIGNOR TO THE TEXTILE-FINISHING MACHINERY COMPANY, A CORPORATION OF RHODE ISLAND

GUIDER

Application filed January 13, 1931. Serial No. 508,459.

This invention relates to a guiding and stretching device for acting upon web material, and relates more particularly to the breaker box or the means for separating the contact members for controlling the movement of the rolls toward and from nipping position; and has for its object to provide a feeler member for engaging the work which shall be electrically insulated from the contact members, whereby no shock or loss of power will be occasioned by engagement of the feeler member with the work.

Another object of the invention is the elimination of vibration of the feeler member.

Another object of the invention is the construction by which the contact members will positively seat to insure even and secure contact while the device is in operation.

A further object of the invention is the provision of a short feeler arm, whereby the motion thereof may be better controlled.

A still further object of the invention is the provision of means for minimizing sparking at the contact points and causing a more even functioning of the device.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of one of the guider units showing the position of the breaker or contact means mounted thereon, which is the subject of this invention;

Fig. 2 is a sectional view through the casing of the contact or breaker unit;

Fig. 3 is a sectional view on the line 3—3 of Figure 2;

Fig. 4 is a section on the line 4—4 of Figure 2; and

Fig. 5 is a diagrammatic view showing the wiring for connecting the electrical guider when in use.

This invention relates to a guider such as disclosed in Patent No. 1,752,966 to E. A. Rusden, dated April 1, 1930, which is elec-

trically operated, one unit of which is shown generally in Figure 1 in this application. This unit comprises a guide plate 10 which is suitably supported on the bracket 11 having a hub 12 for adjustably mounting the same upon the frame of a tentering machine or the like. A roll 13 is rotatably mounted upon the fixed axis 14 which is mounted on the frame 11 and the movable roll 15 is swingably mounted to engage the roll 13 through a slot in the plate 10 (not shown). This roll 15 moves in response to the action of an electromagnet 16, which upon being energized, attracts the armature 17 to swing the roll mounting.

This electromagnet 16 is connected in the electric circuit 18, see Figure 5, connected to the main source of supply 19 through any suitable transformer 20 for reducing the voltage and a rectifier 21 for changing the alternating current of the supply to direct current in the circuit for controlling the electromagnet. Contact members 22 and 23 are positioned in this circuit and are controlled in their action through the feeler member 24 which may be engaged by the edge of the work traveling between the rolls. The contacts are separated to break the circuit and cause the release of the nipping engagement of the rolls due to the release of the armature, and consequent swinging the rolls from nipping position.

The separable contacts are mounted in a casing 25 which is suitably secured to a portion 26 of the framework of the guider unit. Upon the wall 27 of the casing 25 the contact member 23 is fixedly mounted in adjusted position, the same being secured at the end of a threaded rod 28 with the nuts 29 and 30 on either side of the wall 27. A second nut 31 may be provided for connection of this contact member in the electric circuit.

An arm 32 is pivotally mounted upon a pin 33 extending between the walls 34 and 35 of the casing, which arm carries at its free end 36 the contact member 22, while the spring 37 is secured to the wall 38 by the binding post 59 and secured to the arm by means of a rivet 39 and tends to force the

100

contacts 22 and 23 into accurate and positive engagement. This spring 37 conducts current from the binding post 59 to the contact 22.

5 The casing 25 may be of metal, as illustrated, and the parts conducting current will be insulated from the casing as by a fibre washer 40, insulating backing strip 41, insulating bushing 42, insulating washers 10 43 and 44, while in other instances where the casing is made of insulating material such as bakelite, certain types of fibre or similar material, these insulating parts may be eliminated.

15 In order to control the operation of the contact members, I have rotatably mounted a control member 45 upon a pin 46 extending through the walls 47 and 35 of the casing, which member is provided with a cam surface 49 with which engages a fibre projection 50 mounted on the contact arm by means of the rivet 39.

20 The feeler member 24 is secured to the control member 45 so that the feeler will move the member 45 about its axis 46, a movement of the feeler in the direction illustrated by the arrow 51 to dotted line position in Figure 4, will cause separation of the contacts 22 and 23, to break the circuit and permit the work to be drawn back to the center of its travel by the opposite unit, after which the feeler being urged through the spring 37 will follow the work until the contacts 22 and 23 again engage 25 to energize the armature to cause nipping engagement of the rolls. The feeler, however, by being mounted upon this control member may have considerable play without affecting the contacts and thus no vibrations 30 of the feeler or contacts occur. Further, by mounting this unit as illustrated in Figure 1, the feeler arm is relatively short, thus causing better control of the action 35 thereof.

40 For replacement of parts, the pins 33 and 46 may be driven from position and a new arm or control member may be mounted in place, after which the pins will be replaced and their ends spread, as illustrated in Figure 2 to securely hold them in the 45 desired position.

50 Where a frequent interruption of the current occurs, there is apt to be sparking when appreciable voltages are used at the point of breaking the circuit such as at the contact members 22 and 23, and in order to minimize this sparking and better control the action of the device, I have found it desirable to secure a condenser 52 in the electric circuit. The condenser is of a small tubular form and is supported by the bracket 53 secured to the casing 25 and connected to the fixed contact terminal between the nuts 30 and 31. The condenser has one of its plates connected to the electric circuit

55 as at 54 and its other plate connected to the ground as at 55, see Figure 5, and I have found it convenient to ground the condenser by attaching it to the frame of the machine. This condenser in operation eliminates the surge of the current and at the time of breaking stores up the energy until the contacts are again actually in contact.

60 While I have described certain construction forms which embody the principles of my invention, it is obvious that other desired changes in arrangement may be made within the spirit and the scope of the invention as defined in the appended claims.

I claim:

1. In a stretching and guiding apparatus, a pair of units, each unit comprising a pair of rolls arranged to engage the work on opposite surfaces thereof, said rolls being mounted to be relatively moved to and from work nipping position, electromagnetic means for relatively moving said rolls to control nipping position, means connecting said electromagnetic means in an energizing circuit, separable contact means in said circuit, yielding means for causing engagement of said contact means, means independent of said contact means for controlling engagement of said contact means, and a feeler member positioned to be engaged by the edge of the work and operatively connected to said contact controlling means.

65 2. In a stretching and guiding apparatus, a pair of units, each unit comprising a pair of rolls arranged to engage the work on opposite surfaces thereof, said rolls being mounted to be relatively moved to and from work nipping position, electromagnetic means for relatively moving said rolls to control nipping position, means connecting said electromagnetic means in an energizing circuit, separable contact means in said circuit, yielding means for causing engagement of said contact means, a rotatably mounted member separate from said contact means for controlling engagement of said contact means, and a feeler member positioned to be engaged by the edge of the work and operatively connected to said member for controlling said contact means.

70 3. In a stretching and guiding apparatus, a pair of units, each unit comprising a pair of rolls arranged to engage the work on opposite surfaces thereof, said rolls being mounted to be relatively moved to and from work nipping position, electromagnetic means for relatively moving said rolls to control nipping position, means connecting said electromagnetic means in an energizing circuit, separable contact means in said circuit, yielding means for causing engagement of said contact means, a rotatably mounted member separate from said contact means and having a cam surface for controlling engagement of said contact means,

and a feeler member positioned to be engaged by the edge of the work and operatively connected to said contact controlling member.

on opposite surfaces thereof, said rolls being mounted to be relatively moved to and from work nipping position, electromagnetic means for relatively moving said rolls to control nipping position, means connecting said electromagnetic means in an energizing circuit, separable contact means in said circuit, yielding means for causing engagement of said contact means, means independent of said contact means for controlling engagement of said contact means, a casing containing said contact means, yielding means and control means, a feeler member positioned to be engaged by the edge of the work and extending into said casing and operatively connected to said contact control means, and a projection carried by said feeler member for engaging said casing for limiting its movement and causing separation of said contact means.

11. In a stretching and guiding apparatus, a pair of units, each unit comprising a pair of rolls arranged to engage the work on opposite surfaces thereof, said rolls being mounted to be relatively moved to and from work nipping position, electromagnetic means for relatively moving said rolls to control nipping position, means connecting said electromagnetic means in an energizing circuit, separable contact means in said circuit, yielding means for causing engagement of said contact means, means independent of said contact means for controlling engagement of said contact means, a casing containing said contact means, yielding means and control means, a feeler member positioned to be engaged by the edge of the work and extending into said casing and operatively connected to said contact control means, and projections carried by said feeler member for engaging said casing for limiting its movement in both directions.

12. In a stretching and guiding apparatus, a pair of units, each unit comprising a pair of rolls arranged to engage the work on opposite surfaces thereof, said rolls being mounted to be relatively moved to and from work nipping position, electromagnetic means for relatively moving said rolls to control nipping position, means connecting said electromagnetic means in an energizing circuit, separable contact means in said circuit, yielding means for causing engagement of said contact means, means independent of said contact means for controlling engagement of said contact means, a feeler member positioned to be engaged by the edge of the work operatively connected to said contact controlling means, and a condenser connected between one of the separable contact means and the framework of the machine as a ground.

13. In a stretching and guiding apparatus, a pair of units, each unit comprising a pair of rolls arranged to engage the work

on opposite surfaces thereof, said rolls being mounted to be relatively moved to and from work nipping position, electromagnetic means for relatively moving said rolls to control nipping position, means connecting said electromagnetic means in an energizing circuit, a fixed contact member and a movable contact member engaging therewith in said circuit yielding means for causing engagement of said movable member with said fixed member, a rotatably mounted control member independent of said contact member for moving said movable contact member to and from engaging position, a feeler member positioned to be engaged by the edge of the work and operatively connected to said control member, and a condenser connected between one of said contact members and a ground.

14. In a stretching and guiding apparatus, a pair of units, each unit comprising a pair of rolls arranged to engage the work on opposite surfaces thereof, said rolls being mounted to be relatively moved to and from work nipping position, electromagnetic means for relatively moving said rolls to control nipping position, means connecting said electromagnetic means in an energizing circuit, a fixed contact member and a movable contact member engaging therewith in said circuit, yielding means for causing engagement of said movable member with said fixed member, a rotatably mounted control member independent of said contact member for moving said movable contact member to and from engaging position, a feeler member positioned to be engaged by the edge of the work and operatively connected to said control member, and a condenser having one plate connected in the line between the fixed contact member and the source of supply and the other plate grounded.

In testimony whereof I affix my signature.

FRANK A. LANE.
